DESIGN FOR A BICYCLE

Arthur Ely, Elyria, Ohio, assignor of one-half to Arthur G. Smith, Elyria, Ohio

Application April 14, 1934, Serial No. 51,406

Term of patent 14 years

To all whom it may concern:

Be it known that I, Arthur Ely, a citizen of the United States, residing at Elyria, in the county of Lorain and State of Ohio, have invented a new, original, and ornamental Design for a Bicycle, of which the following is a specification, reference being had to the accompanying drawing, forming a part thereof.

Fig. 1 of the drawing shows a side elevational view; and

Fig. 2 shows a plan view from above and with color trimmings omitted, of a bicycle embodying my design.

I claim:

The ornamental design for a bicycle, substantially as shown and described.

ARTHUR ELY.
